ILLUMINATED PHOTO DISPLAY DEVICE

Ralph H. Cooper, Rte. 1, Dixon Springs, Tenn. 37057

Filed Aug. 7, 1972, Ser. No. 278,357

Term of patent 14 years

Int. Cl. D6—07

U.S. Cl. D6—234

FIG. 2

FIG. 1

FIG. 3

FIG. 1 is a front perspective view of an illuminated photo display device embodying my new design;

FIG. 2 is a top plan view;

FIG. 3 is a front elevational view;

FIG. 4 is a rear elevational view;

FIG. 5 is a right side elevational view; and

FIG. 6 is a left side elevational view.

A portion of the fence has been broken away in FIGS. 3-6 for convenience of illustration.

I claim:

The ornamental design for an illuminated photo display device, as shown.
